2 Sheets-Sheet 2

UNITED STATES PATENT OFFICE.

WILLIAM JOSEPH GROOMS, OF KNOXVILLE, TENNESSEE.

ADVERTISING DISPLAY DEVICE.

Application filed April 19, 1924. Serial No. 707,689.

To all whom it may concern:

Be it known that I, WILLIAM JOSEPH GROOMS, a citizen of the United States, residing at Knoxville in the county of Knox 5 and State of Tennessee, have invented a new and useful Advertising Display Device, of which the following is a specification.

This invention relates to an improved means for displaying various advertising 10 matter from an automobile, or other vehicle, as it moves along the street.

The object of my invention is to provide a device in the nature of an endless apron, continuously driven from the running gear 15 of the vehicle as the latter is driven, and adapted to carry advertising cards or placards, which are constantly changing as the vehicle moves along, and more particularly to provide improved means for supporting 20 the endless apron and attaching the display cards thereto in such a manner that they travel with the belt without any chance of their being torn or displaced but may be easily removed and replaced by other cards 25 if desired.

With the above and other objects in view, the invention consists in certain details of construction and combinations of elements, which will be more particularly described 30 in connection with the accompanying drawings illustrating the invention in its preferred form.

In the drawings:

Figure 1 is a side elevation of a motor 35 vehicle equipped with my invention, part of the vehicle body being broken away to better illustrate the construction.

Figure 2 is a plan view of the same with parts shown in section.

Figure 3 is a fragmentary side elevation 40 of the display device, attached.

Figure 4 is a detail sectional view showing the means for attaching the cards or placards.

Figure 5 is a detail sectional view showing 45 the leather spacing strips.

Figure 6 is a detail view in elevation of the means for supporting the endless apron.

Figure 7 is a detail sectional view on the 50 line 7-7 of Figure 6.

The invention is illustrated as installed on a motor vehicle 10, having a body 11 of the type used for delivery purposes, and including a floor 12 and a top 13. Cross bars 55 14 and 15 are secured across the upper part of the body and supported by suitable posts

16 and 17, respectively, of the body frame. Series of vertical rollers 18 are journaled for rotation near the front and rear ends of the body in suitable bearings in the floor 12, and 60 cross bars 15 and 14, respectively. Each of these rollers is provided at its upper end with teeth forming a sprocket wheel 19, over which runs an endless sprocket chain 20. This sprocket chain is so arranged that it 65 passes over the four corner sprocket wheels, and thence to and fro successively about the sprocket wheels of the front and rear interior rollers, as shown in Figure 2. The two rear corner rollers are located somewhat 70 rearwardly of the rear interior rollers so that the rear flight of the chain will clear the same, and as many interior rollers may be provided as is necessary to carry a chain of the length desired. 75

The sprocket chain 20 serves to support an endless apron 21, whose width extends substantially from the top to the bottom of the body, and which is adapted to carry various advertising cards or placards made 80 from tough flexible paper. In order that the apron 21 may be supported in the desired position, certain of the links of the sprocket chain 20 are provided with downwardly projecting clamping ears 22 or other 85 suitable means for clamping the upper edge of the apron, as indicated in Figures 6 and 7.

The face of the apron 21, which is outermost as the apron passes around the sides and rear end of the vehicle body, is divided 90 into rectangular spaces of suitable dimensions by vertical clamping strips 23 which cooperate with corresponding backing strips 24, and are secured thereto by means of small bolts 25 to clamp the edges of the 95 cards or placards 26, which may bear any kind of advertising matter of a firm or individual, who pays for the space.

The strips 23, underneath which the side edges of the cards are clamped, serve to protect the same against being torn, and to guide the same properly as they pass over the rollers. The cards are further protected against contact with the rollers by leather strips 27, which are secured to opposite 100 faces of the apron 21 above and below the cards by means of suitable rivets 28 or the like. The advertising spaces may also be divided longitudinally of the apron and spaced from the rollers by one or more intermediate pairs of strips 27. These leather 105 spacing strips 27 not only serve to protect 110

the upper and lower edges of the cards against being torn, but are particularly desirable in protecting the printed faces of the cards which are inside as they pass over 5 certain of the interior rollers.

Any suitable train of gearing may be provided for driving the apron 21. By way of example, I have illustrated one of the rear interior rollers as provided at its lower end 10 with a beveled gear 29 in mesh with a beveled pinion 30 secured to the rear end of a longitudinal shaft 31, which is provided at its forward end with a gear 32, driven from a stub shaft 33 suitably journaled in the under part of the body 11, and provided with a beveled gear 34 driven from a beveled gear 35 secured to the rear axle, or one of the rear wheels of the vehicle. Any 15 number of the rollers 18 may be thus driven, but it is ordinarily sufficient to provide one such connection, and the other rollers are driven by means of the sprocket chain 20. The rear ratio is preferably such that the apron 21 will be driven slowly, so that spectators will have ample time to read the advertising matter on the cards.

From the foregoing description, it will be understood that as the vehicle is driven along the street, the apron 21 will be continuously driven, and the various cards will successively appear, each in its turn. The strips 23, underneath which the side edges of the cards are secured, and the leather spacing strips 27 will serve as an efficient 30 protection against injuring or soiling the cards. Contracts may be entered into with various firms or individuals for displaying cards with advertisements for a limited 35 period, and the cards may be readily replaced by others when the contract expires, 40 simply by loosening the strips 23 by which they are secured.

While I have shown and described in considerable detail the various features of the 45 invention, it will be understood that these are merely for the purpose of illustrating one form in which the invention may be embodied, and that various modifications 50 may be made therein without sacrificing any of the salient features of the invention. It is therefore my intention to include all such modifications within the scope of the appended claims.

What is claimed is:

55 1. In an advertising display device, the combination with a wheeled vehicle and a series of vertical rollers rotatably carried thereby, one of said rollers being driven by the running gear of the vehicle, of an endless apron trained about said rollers, an 60 endless sprocket chain having links provided with clamping means for securing the upper edge of said apron to support the same, said rollers being formed at their 65 upper ends with sprocket wheels over which

the sprocket chain passes, means for securing a series of advertising cards to the exposed face of the apron, and means secured to opposite faces of the apron to prevent contact of the cards with the rollers. 70

2. In an advertising display device, the combination with a wheeled vehicle and a series of vertical rollers rotatably carried thereby, said rollers being operatively connected to each other and one of them operatively connected to the running gear of the vehicle, of an endless apron mounted to travel about the respective rollers, a series of clamping strips dividing the exposed face of the apron into a plurality of advertising 75 spaces, backing strips cooperating with the clamping strips to removably clamp the opposite edges of a series of advertising cards, so as to hold and protect the same as they travel about the rollers, and flexible card 80 protecting means secured on said apron. 85

3. In an advertising display device, the combination with a wheeled vehicle of a series of rollers rotatably carried thereby, an endless apron carried by said rollers and operatively connecting the same to each other, one of said rollers having a driving connection with the running gear of the vehicle, means for securing a series of advertising cards to the exposed face of said 90 apron, and longitudinal flexible strips secured to opposite faces of the apron above and below the cards and serving to hold the faces of the cards out of contact with the rollers as they pass thereover. 95

4. In an advertising display device, the combination with a wheeled vehicle and a series of rollers rotatably carried thereby, one of said rollers being operatively connected to the running gear of the vehicle, of an endless apron trained about said rollers, said rollers being formed at their upper ends with sprocket wheels, an endless sprocket chain connecting said sprocket wheels and having links provided with clamping means for 100 securing the upper edge of the apron to support the same, a series of vertical clamping strips dividing the exposed face of the apron into a plurality of advertising spaces, and backing strips cooperating with the clamping strips to removably clamp opposite edges of a series of advertising cards, whereby to support and protect the same as they 105 pass over the rollers. 110

5. In an advertising display device, the combination with a wheeled vehicle and a series of rollers rotatably carried thereby, one of said rollers being operatively connected to the running gear of the vehicle, of means operatively connecting the rollers to each other and including an endless apron traveling about said rollers, certain of said rollers being on one side of the apron and certain of the rollers being on the other side thereof, means for securing a series of advertising 115 120 125 130

cards to the exposed face of the apron, and longitudinal flexible strips secured to opposite faces of the apron above and below the cards and serving to hold the faces of the 5 cards out of contact with the rollers as they pass thereover.

6. In an advertising display device, the combination with a wheeled vehicle and a series of vertical rollers rotatably carried 10 thereby, one of said rollers being driven by the running gear of the vehicle, of means operatively connecting the rollers to each other, including an endless apron trained back and forth about said rollers, a series of 15 clamping strips dividing the exposed face of the apron into a plurality of advertising spaces, backing strips cooperating with the clamping strips to removably clamp the opposite edges of the advertising cards to support and protect the same, and longitudinal 20 flexible strips secured to opposite faces of the apron above and below the cards and serving to hold their faces out of contact with the rollers as they pass thereover.

7. In an advertising display device, the combination with a wheeled vehicle and a series of rollers rotatably carried thereby, one of said rollers being driven by the running gear of the vehicle, said rollers being 25 formed at their upper ends with sprocket wheels, of an endless sprocket chain passing

over said sprocket wheels and operatively connecting the rollers to each other, certain links of said sprocket chain having clamping means, an endless apron trained about 35 said rollers and having its upper edge secured in said clamping means, a series of vertical clamping strips dividing the exposed faces of the apron into a plurality of advertising spaces, backing strips cooperating 40 with the clamping strips to removably clamp opposite edges of a series of advertising cards to support and protect the same, and longitudinal leather strips secured to opposite faces of the apron above and below 45 the cards and serving to hold the faces of the cards out of contact with the rollers as they pass thereover.

8. In an advertising display device, a series of rollers rotatably mounted on a supporting member, an endless apron trained about said rollers and operatively connecting the same to each other, means for securing a series of advertising cards to the exposed face of the apron, and flexible strips 50 secured to the apron above and below the cards and serving to hold the faces of the cards out of contact with the rollers. 55

In testimony, that I claim the foregoing as my own, I have hereto affixed my signature. 60

WILLIAM JOSEPH GROOMS.
